UNITED STATES PATENT OFFICE.

WILLIAM C. DOOLITTLE, OF MARION, CONNECTICUT.

IMPROVEMENT IN ADJUSTABLE UMBRELLA-HOLDERS FOR CARRIAGES.

Specification forming part of Letters Patent No. 122,370, dated January 2, 1872.

Specification describing a new and Improved Adjustable Umbrella-Holder, invented by WILLIAM C. DOOLITTLE, of Marion, in the county of Hartford and State of Connecticut.

Figure 1 is a side view of my improved holder. Fig. 2 is a top view of the same.

Similar letters of reference indicate corresponding parts.

My invention has for its object to furnish an improved umbrella-holder for attachment to the seats of buggies or other wagons, which shall be simple in construction, inexpensive in manufacture, and convenient in use, and which shall at the same time be so constructed that it may be readily adjusted to hold the umbrella inclined at any desired angle; and it consists in the construction and combination of the various parts of the holder, as hereinafter more fully described.

A is the base piece of the holder, which is made with two arms projecting horizontally, and at such a distance apart as to receive the seat-board or other suitable support between them, to which they are secured by a hand-screw, B, which passes up through the lower arm, and the end of which presses against the said board or support. The forward end of the screw B may have a pronged disk or button swiveled to it to rest against the said support and prevent it from being injured by the end of the said screw. To the upper end of the clamp A is attached, or upon it is formed, a short post, C, having a hole or socket formed in its upper end to receive a round tenon formed upon the lower end of the post or rod D, where it is adjustably secured in place by a hand-screw, E, so that by simply loosening the screw E the post or rod D may be turned or adjusted as desired. Upon the upper end of the rod or post D is formed a semicircular cross-head, d¹, which enters a slot in the lower end of the rod or post F. The cross-head d¹ is made with an upwardly-projecting lug, d², through which and through the lower slotted end of the rod or post F passes the rivet, screw, or bolt that pivots the said rod or post F to the rod or post D. The rod or post F is secured in place when adjusted by the hand-screw d³, which passes through one or both parts of the slotted lower

end of the said rod or post F and into a recess or hole formed in the cross-head d¹, several recesses or holes being formed in the said cross-head to receive the said screw to enable the rod or post F to be secured at any desired angle. Upon the upper end of the rod or post F is formed, or to it is attached, a two-armed bar, G H, the arms of which project at right angles with the rod or post F and with each other, as shown in Figs. 1 and 2. To the outer end of the longer arm G is attached, or upon it is formed, a plate or jaw, I, which is concaved upon its inner side to fit upon the handle of the umbrella. J is a plate or jaw, the outer side of which is concaved to fit upon the umbrella-handle. In the middle part of the side edge of the plate or jaw J is formed a notch to receive and fit upon the arm G. The arm G is slotted longitudinally to receive a screw, K, which screws into the edge of the plate or jaw J to hold it close up to the said arm G. L is a hand-screw, which passes through a screw-hole in the arm H parallel with the arm G, and its forward end is swiveled to the plate or jaw J, so that by turning the screw L in one direction the jaw J will be moved outward to clamp the umbrella-handle between the jaws I and J, and by turning the said screw in the other direction the jaw J will be moved back to release the said handle.

By this construction the umbrella will be held securely, and may be conveniently adjusted or inclined in any direction as the direction of the wind may render necessary.

Having thus described my invention, I claim as new, and desire to secure by Letters Patent—

An improved adjustable umbrella-holder, formed by the combination of the clamp A, swiveled and jointed post or rod C D d¹ d² F, two-armed bar G H, plates or jaws I J, and screws or equivalent fastenings L K d³ E B with each other, substantially as herein shown and described, and for the purpose set forth.

WILLIAM C. DOOLITTLE.
